HOCKEY STICK BLADE

Raymond W. Leclerc, Leominster, Mass.,
(% Mylec Inc., Winchendon Springs, Mass. 01477)

Filed Aug. 13, 1971, Ser. No. 171,804

Term of patent 14 years

Int. Cl. D21—02
U.S. Cl. D34—5 BC

Fig. 1.

Fig. 2.

Fig. 3.

Fig. 4.

FIG. 1 is a view in side elevation showing my hockey stick blade;

FIGS. 2 and 3 are left and right end views respectively looking in the direction of the respective arrows in FIG. 1, and

FIG. 4 is a bottom view looking in the direction of arrow 4 in FIG. 1.

The distinctive characteristics of my design reside in the representation of the ribs appearing at both sides of the blade adjacent the connection with the stick.

I claim:

The ornamental design for a hockey stick blade, and described as shown.
